UNITED STATES PATENT OFFICE.

JOHN FITZPATRICK, OF ASTORIA, NEW YORK.

DESIGN FOR A RADIATOR INCLOSURE.

Application filed March 20, 1928. Serial No. 25,928. Term of patent 7 years.

To all whom it may concern:

Be it known that I, JOHN FITZPATRICK, a citizen of the United States of America, residing at Astoria, Queens County, city and State of New York, have invented a new, original, and ornamental Design for a Radiator Inclosure, of which the following is a specification, reference being had to the accompanying drawing, forming part hereof, in which Figure 1 is a top plan view of a ra-

dior inclosure showing my new design, and Figure 2 is a front elevation thereof.

The ornamentation shown is continued throughout.

I claim:

The ornamental design for a radiator inclosure, as shown and described.

Signed at New York city, New York, this 19 day of March, 1928.

JOHN FITZPATRICK.
